(57) CLAIM

The ornamental design for a display panel portion with a computer icon, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display panel portion with a computer icon showing my new design.

The broken line bordering the FIGURE and illustrating the display panel portion with a computer icon forms no part of the claimed design.
